UNITED STATES PATENT OFFICE.

JOHN S. CULLEY, OF LOUISVILLE, KENTUCKY.

WALL FOR BUILDINGS.

No. 897,353.

Specification of Letters Patent.

Patented Sept. 1, 1908.

Application filed May 12, 1905. Serial No. 260,141.

To all whom it may concern:

Be it known that I, JOHN S. CULLEY, a citizen of the United States, residing at Louisville, in the county of Jefferson and State of Kentucky, have invented certain new and useful Improvements in Walls for Buildings, of which the following is a specification.

The present invention relates to improvements in walls for buildings and particularly to that class of walls which include in their construction a frame support and an outer facing of stone blocks which are each attached to the frame support by suitable means.

The object of the invention is to provide means for connecting the blocks forming the outer facing of the wall to the inner support, which will securely hold said blocks in position and be entirely concealed from view.

A further object is to provide a supporting means for said blocks which can be more readily secured to the frame support than has been possible with the devices heretofore proposed.

The invention is illustrated in the accompanying drawings, in which,—

Figure 1 is a vertical sectional view of a wall constructed in accordance with the present invention; Fig. 2 is a horizontal section, on the line 2—2 of Fig. 1; Fig. 3 is an elevation of a section of wall constructed in accordance with the invention; Fig. 4 is a section on the line 4—4 of Fig. 2; Fig. 5 is a detail view of the block hanger; Fig. 6 is a side view of a slightly different form of hanger.

Referring to the drawings, the inner section of the wall or frame support consists of a series of uprights or studs 1, which are connected on one side by suitable sheathing boards 2. To the said frame support are connected the blocks 3 forming the outer facing of the wall said blocks being attached to said support by suitable hangers. As shown each of said hangers is formed from a flat metal bar or plate which is bent at an intermediate point of its length to provide two sections 4, 5, which extend at an obtuse angle to each other. The section 4 which is inclined downwardly from the section 5 is secured within the block 3 and said section 5 extends upwardly from said section 4 and above the block in rear thereof into position to be secured to the aforesaid frame support.

The section 5 of the hanger is provided with

a plurality of apertures to receive the fastening devices hereinafter referred to.

Preferably, as shown in the drawings, the blocks 3 will be formed from cement or other suitable material and the hangers for attaching said blocks to the frame support will be embedded therein while the block is being molded. To positively prevent the hangers from being withdrawn from the block a supplemental cross bar or pin 7 may be connected with the lower end of the hanger, said pin projecting beyond both sides of the hanger section 4 and being securely embedded in the block 3. The lower end of the hanger section 4 is bent upon itself to form a hook or sleeve through which the pin 7 extends.

This construction provides a firm and durable connection between the hanger and body of the block. The body of the hanger being formed from a flat plate, a relatively large surface is engaged in a vertical direction to the body of the block, and the inner end of the hanger, being extended laterally on opposite sides of the body thereof, is held against any movement in a horizontal direction. That is, the rod 7 forms with the member 4, a substantially T-shaped device which affords a relatively large contact or holding surface to the body of the block. Another very important advantage of the device is its simplicity. There are but two members, the main one being the flat plate 4, 5, and the supplemental or additional member being the rod 7. This device is, as before pointed out, adapted to so engage the body of the block as to be positively held against movement in any direction relative thereto.

It will be seen that the upwardly extending sections 5 of the hangers of each tier of blocks of the wall facing will be concealed by the blocks on the next highest tier so that when the wall is completed the hanger will be concealed and the finished wall will have the appearance of a wall constructed entirely of stone or similar material in the ordinary manner. The hangers may be attached to the frame support by nails 6 of ordinary form. It will be noticed that as each block 3 is placed in position the section 5 of the hanger or hangers thereof will be exposed and can be secured to the frame support by the workman placing the block in position. That is all of the operations required to construct the facing of the wall and connect the same to the frame support can be performed

in front of said support. This is of great practical advantage as by it a wall can be more expeditiously and cheaply constructed than when it is necessary to employ special 5 fastening means in rear of the frame support to hold the blocks in engagement therewith. As pointed out above each block 3 conceals the section 5 of the hanger of the block on which it rests and in addition each block by 10 bearing against the front face of the section 5 of the hangers of the lower block acts as a fastening means, additional, or supplemental, to the nails or similar fastening devices 6, for holding the lower block in position. In 15 the embodiment of the invention illustrated the blocks 3 of the different tiers are connected by interlocking tongues and grooves as at 8.

The blocks may be of any suitable form 20 and size and each is provided with any desired number of hangers or means for attaching the block to the inner frame support. In the embodiment of the invention illustrated, each block is provided with two 25 of said hangers and in the rear face or surface of each block are formed recesses 9 which reduce the weight of the block and provide air spaces or chambers within the wall. It will be understood however that the blocks may 30 be of different form if desired and that also they may be made in any suitable manner. They may be solid slabs instead of having recesses or grooves formed therein, as at 9 and the invention may be carried out by using 35 natural stone blocks instead of composite, artificial blocks such as have been before referred to.

A wall constructed in accordance with the present invention will present the appearance 40 of a solid stone wall and while having substantially all of the advantages of such a solid wall can be more readily and cheaply built.

Instead of making the hangers in the form 45 shown in Figs. 1 to 5 inclusive, they may be made in the form shown in Fig. 6 in which the section 4^a forms substantially a right an-

gle with the vertical section 5^a. As shown the vertical sections of the hangers project slightly from the rear face of the blocks, but 50 it will be evident that if desired the hangers may be so connected with the blocks that their rear face will lie flush with the rear surface of the block.

Having fully described my invention what 55 I now desire to secure by Letters Patent is:

1. The herein described wall facing block, composed of a body of cement or other suitable material, and a hanger formed of a bent, flat, metal plate having one section embedded in the block and another section projecting from and extending parallel to the rear face of the block at an obtuse angle to the embedded section and adapted to be connected directly to a suitable support, said plate having oppositely extending lateral projections at the inner end of its embedded section, substantially as and for the purpose described. 65

2. The herein described wall facing block, 70 composed of a body of cement or other suitable material, and a hanger comprising a bent, flat, metal plate having one section embedded in the block and projecting through the rear face thereof and another 75 section projecting therefrom at an obtuse angle and extending parallel to said rear face of the block and adapted to be connected directly to a suitable support, the inner end of the embedded section of said plate being bent 80 upon itself to provide a hook or sleeve, and a bar or pin extending through said hook or sleeve and projecting beyond the side edges of the plate, whereby the inner end of the hanger is wider than the body, substantially 85 as and for the purpose described.

In testimony whereof I have signed my name to this specification in the presence of two subscribing witnesses.

JOHN S. CULLEY.
